(57) **CLAIM**

The ornamental design for an adjustable automobile bumper protector, as shown and described.

DESCRIPTION

FIG. 1 is a front perspective view of an adjustable automobile bumper protector showing my new design.

FIG. 2 is a rear perspective view thereof.

FIG. 3 is a top perspective view thereof; and,

FIG. 4 is a front perspective view of the adjustable automobile bumper protector detachably secured to a bumper of an automobile.

The broken line portions shown in FIG. 4 of the drawing are for illustrative purposes only and form no part of the claimed design.
